Stanley D. Harrison, Los Angeles, Calif., assignor to
Mole-Richardson Co., Hollywood, Calif., a corporation
of California

Filed May 5, 1967, Ser. No. 6,970

Term of patent 14 years

(Cl. D48—20)

FIG. 1.

FIG. 2.

FIG. 3.

FIG. 4.

FIGURE 1 is a front perspective view of a floodlight for photographers or the like showing my new design;

FIGURE 2 is a rear perspective view;

FIGURE 3 is a front perspective view of a modified form of the floodlight for photographers or the like which is shown in FIGURES 1 and 2; and

FIGURE 4 is a rear perspective view of the modified form shown in FIGURE 3.

The support brackets and electric cables are shown for illustrative purposes only.

The pattern of perforations present throughout the figures has been fragmentarily shown for convenience of illustration and is understood to be uniform throughout the areas so shaded.

I claim:

The ornamental design for a floodlight for photographers or the like, as shown and described.
